DESIGN FOR AN AUTOMOBILE TRANSPORT BODY

James Rodney Weeks, Birmingham, and Rudolph H. Helms, Melvindale, Mich., assignors to Whitehead & Kales Company, River Rouge, Mich., a corporation of Michigan

Application April 12, 1937, Serial No. 68,715

Term of patent 14 years

To all whom it may concern:

Be it known that we, James Rodney Weeks and Rudolph H. Helms, a citizen of the United States of America and a citizen of the Republic of Germany, respectively, residing at Birmingham and Melvindale, in the counties of Oakland and Wayne, respectively, and State of Michigan, have invented a new, original, and ornamental Design for an Automobile Transport Body, of which the following is a specification, reference being had therein to the accompanying drawing, forming a part thereof, wherein:

Figure 1 is a top plan view of an automobile transport body showing our new design;

Figure 2 is a side elevation thereof;

Figure 3 is a rear elevation thereof.

The dominant feature of the invention is the open-work superstructure of the body.

We claim:

The ornamental design for an automobile transport body substantially as shown and described.

JAMES RODNEY WEEKS.
RUDOLPH H. HELMS.
